[57] CLAIM

The ornamental design for a carver's vise, as shown.

DESCRIPTION

FIG. 1 is a front perspective view of the carver's vise showing my design;

FIG. 2 is a first side view of the carver's vise;

FIG. 3 is a second side view of the carver's vise;

FIG. 4 is a rear view of the carver's vise;

FIG. 5 is a top view of the carver's vise;

FIG. 6 is a bottom view of the carver's vise;

FIG. 7 is a perspective view of the carver's vise;

FIG. 8 is a first side elevational view of the carver's vise;

FIG. 9 is a second side elevational view of the carver's vise;

FIG. 10 is a rear elevational view of the carver's vise;

FIG. 11 is a top plan view of the carver's vise; and,

FIG. 12 is a bottom plan view of the carver's vise.

The broken line portions of the disclosure are for illustrative purposes only and form no part of the claimed design.
